GERMANY, AND DAVID J. UHLE, OF ALLENTOWN, PENNSYLVANIA.

ROTARY FURNACE.

Application filed February 25, 1927, Serial No. 171,029, and in Germany January 31, 1927.

Our invention relates to improvements in rotary furnaces, and more particularly in rotary furnaces of the type in which preheating, calcining, burning and cooling chambers are provided in axial alignment. One of the objects of the improvements is to provide a furnace of this type in which the heating drum proper including in some cases the preheating, calcining and burning chambers is independent of the cooling chamber or drum, so that the said cooling drum can be removed and access can be had to the heating drum in the pauses of the operation of the furnace the cooling drum being either coupled to the heating drum at desired times, or being independently driven by means acting in accurately timed relation with the drive for the heating drum.

Rotary furnaces without cooling drums are well-known. It is often difficult to build a cooling drum into the length of the furnace, as this must be of substantial length to provide for effective cooling of the burnt material. Furthermore, such addition renders observation of the fire very difficult. Arrangement of a cooling device in a pit underneath the rotary furnace, in a manner known in the art would cause much inconvenience due to the necessary excavating and the difficulty of handling the clinkers formed in the process of combustion. Our construction avoids these disadvantages, and has also the advantage that it brings the cooling air into very intimate engagement with the clinkers and other solid residue of combustion so that the cooling path may be made a short one. Another object of the improvements is to provide a furnace in which the heating drum can be inspected through the cooling drum, and with this object in view our invention consists in providing a pipe extending through the cooling drum to a point near the heating drum and constructed so as to permit inspection of the charge within the heating drum. Other objects of the invention will appear from the following description.

For the purpose of explaining the invention an embodiment of the same has been shown in the accompanying drawing in which the same reference characters have been used in all the views to indicate corresponding parts. In said drawing,

Fig. 1, is a sectional elevation showing the

rear part of the heating drum of the furnace and the cooling drum,

Fig. 2, is a sectional elevation taken on the line 2—2 of Fig. 1,

Fig. 3, is a sectional elevation taken on the line 3—3 of Fig. 1,

Fig. 4, is a detail sectional view on an enlarged scale showing a modification of the construction of one of the concentric cylinders forming the cooling drum,

Fig. 5, is a detail sectional view on an enlarged scale of an air tight sliding joint.

As shown in the figures, the furnace comprises a rotary heating drum *a* and a cooling drum disposed in axial alignment therewith, both drums being slightly inclined relatively to each other from the intake end to the delivery end thereof. In the example shown in the drawing the cooling drum comprises three concentric cylinders viz a cylinder *b*, a cylinder *c* disposed concentrically within the cylinder *b*, and a cylinder *d* disposed concentrically around the cylinder *b*, the said cylinders being suitably connected with each other. The inner cylinder *b* extends to and surrounds the delivery end of the heating drum *a*, but it is disconnected therefrom. As shown, flanges 5 and 6 are secured respectively to the ends of the heating drum *a* and the cooling drum *b*, which flanges abut against each other. The inner cylinder *c* extends from the intake end of the cooling drum to a point spaced from the rear wall *b*¹ of the cylinder *b*, so that an annular space *e* is provided at the rear end of the cylinder *b*, through which space the interior of the cylinder *c* communicates with the annular chamber provided between the cylinders *c* and *b*.

At its front end the cylinder *c* is connected with the cylinder *b* by a flange 7. The outer cylinder *d* is connected at its front end with the cylinder *b* by a ring 8, and its rear end projects into an annular casing *h*, which casing is in air-tight engagement respectively with the cylinders *b* and *c*, the joint between the said parts being constructed so as to permit relative displacement of the parts, as is necessary in view of the expansion by heat.

Within the inner cylinder *c* there is a pipe *g*, which extends from the end wall *b*¹ to a point near the delivery end of the heating drum *a*, and which is constructed so as to permit inspection of the inner parts of the heating

drum and the charge contained therein from the rear end of the cooling drum, the said pipe *g* being suspended from the drum *b*, *c*, *d* so as to permit independent expansion by heat in longitudinal and transverse directions. At its outer circumference the pipe *g* carries longitudinal elevating ribs *g*¹ which, as shown in Fig. 2, are U-shaped in cross-section, so that they act in the way of scoops elevating the material moving longitudinally through the cylinder *c*. To the outer circumference of the cylinder *c* elevating ribs *f* are secured, which are constructed so as to carry the material from the right of the drum to the left, and by means of which the cylinders *c* and *b* are connected with each other. Between the cylinders *b* and *d* elevating ribs *d*¹ of double-T-form are provided, and as appears more particularly from Fig. 2, the said ribs are alternately fixed to the inner and outer cylinders. We have found that by thus mounting the ribs the material being conveyed between the cylinders is effectively distributed and exposed to the action of the cooling air. The annular casing *h* is provided at its lower end with a discharge pipe *h*¹ constructed according to the German Patent 354,777 provided with a gate for closing the same and adapted to deliver the material into a suitable conveyor 9. Preferably the cylinder *c* is provided internally with strengthening rings, and at its delivery end it is formed with a disintegrating chamber *i* containing for example steel balls 11 for disintegrating the burnt material to the desired size, for example to the size of walnuts or hazelnuts. Preferably the reinforced wall of the said disintegrating chamber is provided with lugs 10 adapted to elevate the balls 11 to the desired height and permitting the material to be disintegrated to pass between the same. Thus by the falling balls the larger pieces of baked material clinkers, etc. are broken, so that the said material can more readily flow through the annular chambers provided between the cylinders *b*, *c*, *d*, and cooling is made more effective, the small pieces being more readily and completely cooled than big ones.

At the rear end of the drum *b*, *c*, *d* there is a relatively stationary lid or casing *k* which is connected with the cylinder *b* in an airtight manner, the joint between the parts permitting expansion of the drum by heat and also permitting twisting and other movements occurring in the course of the operation of the apparatus. Through the rear wall of the casing or lid *k* a pipe *m* is passed into the cooling chamber, which pipe extends through the said chamber and into the heating chamber *a* where it is provided with a nozzle *o* for the delivery of the heating medium. At the front end the said pipe is suitably supported within the pipe *g* by means of arms *n* and a suitable bearing supported by said arms.

The drum *b* is mounted on two rings *p* supported on four rollers *q* disposed on a carriage *r*, the said carriage being adapted to move the cooling drum away from the heating drum *a*.

At the rear end of the drums *b*, *c*, *d* one or more pipes *t* are provided which extend through the rear wall of the lid *k* and into the drum, and the said pipe or pipes are provided with means for injecting regulated amounts of water into the cooling chamber and on the burnt material. The amount of the said water is such that after being vaporized on the hot clinkers the steam passing over the glowing material coming from the heating drum into the cooling drum, which material has a temperature of much more than 1000° C., is dissociated, into hydrogen and oxygen. Thus a very effective combustion of the carbon supplied through the pipe *m* and the nozzle *o* is insured, and we are enabled to use hard coal or anthracite containing little or no gaseous matter, which coal would otherwise not be easily ignited within the furnace.

To reduce the waste of heat by radiation we provide the cylinder *b* with insulating material *u*, as is shown in Fig. 4.

Suitable means are provided for imparting rotary movement to the cooling drum *b*, *c*, *d*. To show what may be done, an electromotor (Fig. 3) is mounted on the carriage *r* and connected with one of the rollers *q* through the intermediary of suitable gearing. But we wish it to be understood that our invention is not limited to a construction in which separate driving means are provided for the drum *b*, *c*, *d*, and that in some cases clamping means or claws may be provided for connecting the said drum with the heating drum *a*, so that common driving means are provided for the heating drum *a* and the cooling drum *b*, *c*, *d*.

In the operation of the furnace the burnt material or clinkers delivered from the heating drum *a* gradually proceed along the inner wall of the cylinder *c* to the right and downwardly, whereupon they are disintegrated within the disintegrating chamber *i*. The disintegrated materials fall from the cylinder *c* into the space *e*, whereupon they are carried by the feeding ribs *f* from the right to the left and towards the heating drum *a*. At the left-hand end of the annular chamber included between the drums *b* and *c* the material drops through holes *b*² made in the cylinder *b* into the annular chamber provided between the cylinders *b* and *d* in which they are gradually carried to the right and into the casing *h*, from which they are discharged on the conveyor 9.

The air for supporting combustion within the furnace *a* is passed through the annular chambers provided between the cylinders *b*, *c* and *b*, *d* and through the inner part of the

cylinder *c* in a direction opposite to the movement of the burnt material. Thus the length of travel is a multiple of the length of the cooling chamber, so that the baked material is effectively cooled, and the air is preheated to a high temperature. The air is admitted to the casing *h* through an inlet *x* in the spout *h'*, suitable means being provided for regulating the amount and the pressure of the air, and 10 after passing through each of the annular chambers of the cooling drum in a direction contrary to the movement of the burnt material, it is delivered into the heating drum *a*, where it is used for burning the fuel injected 15 through the burner *o*.

The casing *h* as well as the lid *h* are in air-tight engagement with the cylinders *b* and *d*, suitable sliding joints being provided for this purpose. Thus there is no access of fresh air 20 from without to the inner part of the cooling drum, and no escape of compressed air from the drum to the outer air.

While in describing the invention reference has been made to a particular example embodying the same we wish it to be understood 25 that our invention is not limited to the construction shown in the drawing, and that various changes may be made in the general arrangement of the apparatus and the construction 30 of its parts without departing from the invention. The cooling drum can for instance comprise more than three concentric cylinders.

We claim:

1. A rotary furnace comprising a rotary heating drum, heating means, a rotary cooling drum in axial alignment with said heating drum and removable therefrom, said cooling drum comprising a plurality of concentric cylinders having annular chambers provided between the same communicating respectively with the inner part of the cooling drum and with each other at opposite ends, elevating ribs projecting from said drums into said annular chambers, disintegrating means within said cooling drum, and means for rotating said drums.

2. A rotary furnace comprising a rotary heating drum, heating means, a rotary cooling drum in axial alignment with said heat-

ing drum and removable therefrom, said cooling drum comprising a plurality of concentric cylinders having annular chambers provided between the same communicating respectively with the inner part of the cooling drum and with each other at opposite ends, elevating ribs projecting from said drums into said annular chambers, disintegrating means within said cooling drum at the delivery end of the inner passage thereof, and means for rotating said drums.

3. A rotary furnace comprising a rotary heating drum, heating means, a rotary cooling drum in axial alignment with said heating drum and removable therefrom, said cooling drum comprising a plurality of concentric cylinders having annular chambers provided between the same communicating respectively with the inner part of the cooling drum and with each other at opposite ends, elevating ribs projecting from said drums into said annular chambers, the ribs projecting into one of said annular chambers being alternatingly carried by the outer and inner cylinders, and means for rotating said drums.

4. A rotary furnace comprising a rotary heating drum, heating means, a rotary cooling drum in axial alignment with said heating drum and removable therefrom, said cooling drum comprising a plurality of concentric cylinders having annular chambers provided between the same communicating respectively with the inner part of the cooling drum and with each other at opposite ends, elevating ribs projecting from said drums into said annular chambers, a discharge chute provided at the delivery end of the outer cylinder and in air-tight engagement therewith and with the next cylinder of the drum, means for rotating said drums, and one or more pipes with means for injecting regulated amounts of water into the cooling chamber between the intake end and the delivery end of the cooling drum.

In testimony whereof we have hereunto set our hands.
